OSCILLATION TRANSLATING DEVICE

Michael J. Di Toro, East Orange, N. J., assignor
to Thomas A. Edison, Incorporated, West
Orange, N. J., a corporation of New Jersey

Application June 23, 1937, Serial No. 149,861

13 Claims. (Cl. 274—1)

This invention relates to oscillation translating devices, such as those for the translating of acoustic or electric oscillations into mechanical oscillations, or vibrations.

It is a broad object to provide improved means for reducing or suppressing undesired vibrations of an oscillation translating device.

While no unnecessary limitation thereto is intended, the invention has especial utility, and has been primarily described, in connection with phonographic apparatus for the recordation of sound-representing oscillations upon a moving record; and an especial aspect of the invention is concerned with the reduction or suppression of certain undesirable resonance effects, usually of low frequency, in the operation of the recorder. Properly to understand these effects, it is first desirable to note the fact that in the operation of impressing or cutting of a moving record by a recorder arranged for movement toward and away from the record, the greater the depth of penetration in the record of the immediate record-cooperating portion or tool of the recorder, the greater is the force tending to move this portion or tool out of the record. This is an obedience to the characteristic of restoring force increase accompanying displacement increase, which is the characteristic of a compliance or spring. Accordingly the moving record may be considered as characterized by an effective or dynamic compliance (the precise value of which is dependent on record speed, recorder tool shape and nature, record material, etc., but which is not to be confused with the static compliance of the record itself). With this dynamic compliance of the record (or a compliance principally made up thereof) there are capable of resonating certain effective masses of the recorder. The objectionable effects in question comprise so much of the vertical vibrations of the recorder tool as are the result of this resonance.

Various means are already known for mitigating these effects, but they are characterized by one or more of the deficiencies of very imperfect action, criticalness of required adjustments, impairment of intended free movement of the recorder or its portion toward and away from the record, and the like.

It is an object of my invention to reduce or suppress these resonance effects in more efficient manner.

It is an object to perform such reduction or suppression without any requirement for critical adjustment of components of the system.

It is an object to perform such reduction or

suppression without impairing the desirable free movement of the recorder toward and away from the record.

It is another object to provide an improved oscillation recorder, and an improved recording system, in the operation of which these effects are reduced or suppressed.

Other and allied objects will more fully appear from the following description and the appended claims.

In the description reference is had to the accompanying drawing, of which—

Figure 1 is a partly elevational and partly vertical cross-sectional view of a recorder wherein my invention has been embodied, additional elements of the recording system being shown schematically;

Figure 2 is a plan view of the recorder of Figure 1;

Figure 3 is a plan view of a recorder wherein my invention has been embodied in modified form;

Figure 4 is an end view of the recorder of Figure 3;

Figure 5 is a vertical cross-sectional view of a loudspeaker embodying a feature of my invention;

Figure 6 is a vertical view taken along the line 6—6 of Figure 5; and

Figure 1a is a fractional view, of the nature of Figure 1, but illustrating a recorder wherewith my invention has been embodied in a further modified form.

Before describing my invention proper I may first describe a purely typical recorder to which it has been applied and with which it has been illustrated in Figures 1 and 2. This recorder appears as V, being arranged for the recordation of oscillations upon the record R; purely by way of example, this record has been shown as a cylindrical one, arranged for rotation by means not herein necessary to show. The recorder has been shown pivoted, for movement toward and away from the record, to a non-vibratile standard 1 (for example arranged for slow propulsion transversely or longitudinally of the record by means not herein necessary to show).

The recorder V may comprise a main portion in the form of a frame or casing 3, pivoted to the pivots 2 in standard 1 as by the two arms 13 of the bracket 14 secured on the top of the casing at one of the extremities of the latter; and a portion vibratable in accordance with input oscillations and supported by the main portion. By way of example this second portion has been shown as an electrically vibratable one, in the form of a piezo-electric bending unit 4 of the so-

called "bi-morph" type—e. g., comprising two thin crystals secured face-to-face and arranged for simultaneous voltage application in such manner that one crystal expands longitudinally 5 as the other contracts, and vice versa, to result in a transverse (as shown, up-and-down) bending of the unit. The unit 4 has been shown secured at its right-hand extremity in a recessed metal base 3a fastened within the frame or casing 3, 10 so that its left-hand extremity is available for up-and-down vibration within the casing in accordance with electric oscillations applied across the electrical leads 4a; these leads may pass insulated out from the unit—for example, 15 to a source of such oscillations comprising an amplifier A fed by microphone M. Secured on the left-hand extremity of the unit 4, and extending outwardly through the suitably apertured bottom of the casing, is a holder 5a, in the 20 bottom of which is held the tool or stylus 5 adapted to engrave the record.

Somewhat to damp excessive high-frequency peaks of the unit vibration, to render the unit effectively somewhat less fragile, or for allied 25 purposes, it is frequently desirable in recorders of this construction to provide rubber pads or other damping means between the unit and the top and bottom, respectively of the casing 3; such pads have been fractionally illustrated as 30 12 in Figure 1. It is to be understood, however, that such damping function as these perform is a secondary function only, substantially significant only at high frequencies; and that these 35 pads are not to be confused with the special damping means which I shall hereinafter describe.

It will be understood that in this structure the tool 5 is biased against the record R by the effective mass of the recorder V as seen at the tool 40 5; and that, the record being rotated and the standard I being slowly moved longitudinally of the record, the tool will engrave in the record a spiral groove. Should the surface level of the record as presented to the tool vary slightly up 45 and down with each revolution of the record (as because of a slight "out-of-round" condition of the record as rotatively supported) the pivoted recorder and tool are nevertheless free to follow this surface level; and the tool will penetrate the record surface to a generally constant groove 50 depth predetermined by the record and tool characteristics and by the bias above-mentioned. If at the same time electric oscillations be applied across the unit leads 4a, an oscillatory bending force will be developed in the unit 4, 55 vibrating the tool 5 up and down relative to the balance of the recorder, or casing 3. The casing, though free of external restraints against movement relative to the record, is largely inhibited 60 from such movement by reason of its own inertia; accordingly, over the greater part of the useful frequency spectrum, most of the vibration of the tool relative to the casing will appear as an absolute vibration of the tool —i. e., relative 65 to the record surface—wherefore oscillations representing undulations will be efficiently created in the groove which the tool is engraving.

The vibration of the tool 5 relative to the casing, which gives rise to the desired absolute tool vibration, is (assuming constant input oscillation amplitude) a gradually varying function of frequency. This statement applies excepting in a frequency region around the frequency of resonance between (a) a compliance made up of 70 the compliance of the unit 4 and the dynamic

record compliance, in parallel, and (b) the effective mass, as seen by the record, of the casing with pads 12 and of unit 4 with tool-holder 5a and tool 5—i. e., of the entire recorder. In this frequency region the vibration of the tool 5 relative to the casing may attain inordinately high values; attendantly the vibration of each of these elements relative to the record R will become inordinately high, a complex amplitude and phase relation existing between the three 10 vibrations in question. These undue amplitudes of vibration occur whenever the matter to be recorded contains components lying in the frequency region just mentioned; they cause serious distortion in the recordation, both by seriously 15 exaggerating the amplitudes of these components and by causing "hang-over" effects therefrom (i. e., finite continuances of these components in the recordation after their termination in the oscillations to be recorded). 20

Broadly, there is known the use of simple damping means for the tool or vibratable element of the recorder—such means are comprised, for example, in the pads 12 which have been illustrated in the drawing herein but which form 25 no immediate part of the present invention. The use of simple damping of the tool or vibratable recorder portion, however, is rather ineffective to prevent the unfavorable effects which are herein specifically considered. 30

For vibration suppression generally there is known a more elaborate system, frequently termed a "damped vibration absorber"; this has been described in general terms and at length by J. P. Den Hartog on pages 103 through 117 of 35 his book entitled "Mechanical Vibrations" (1934, McGraw-Hill). Briefly, this damped vibration absorber consists of an anti-resonant mechanical system or structure which is tuned to the frequency of the vibration to be suppressed (or 40 to a frequency slightly lower than that frequency) and provided with suitable damping. This damped vibration absorber has been disclosed in one instance in connection with vibration translating devices—in United States Letters Patent 45 No. 2,031,948 to Harrison. In this instance, however, not only has it been employed for the suppression of a high frequency resonance occasioned in reproduction by the actual record compliance (as distinguished from low frequency 50 resonance occasioned in recordation by the dynamic record compliance), but also it has been associated immediately with the record-cooperating tool or vibratable portion of the translating device, as distinguished from the main portion 55 of the device. According to the instant invention, I employ a damped vibration absorber which, in theoretical fundamentals, is of the type disclosed by Den Hartog; I immediately associate it, however, with the main recorder portion 60 and not with the portion vibratable by the input oscillations—and in spite of the apparently continued vibratory freedom of the vibratable portion, the absorber efficiently suppresses the objectionable resonance effects above discussed. 65

For forms of vibration absorber, I have devised certain resilient, damped, beam structures. In one of these, which I have preferred, the structure is of the "clamped-free" beam, or cantilever, variety; this, applied to the described 70 recorder, has been illustrated in detail in Figures 1 and 2 of the accompanying drawing. Therein will be seen a clamp 6 secured to the frame or casing 3, as through the medium of the bracket 14, to which it may be welded; pass 75

ing through this clamp, for drawing its top and bottom together, may be the screws 8, and surrounding each screw for almost its full length within the clamp may be a respective stop bushing 7. Clamped between the tops of the stop bushings 7 and the clamp 6 is one end of a wide spring 9, which may extend from the clamp in the direction away from the pivots 2, above the casing 3; the other end of this spring may be doubly folded over to provide the spring clamp 10. The anti-resonant structure is completed by the damping means 11, which has been shown terminally held in the clamp 6 and in the spring clamp 10. The beam structures which I utilize, including the one just described, readily permit for this means the employment of a block or slab of one of the presently available damping materials of low resiliency and high internal resistance to deformation (i. e., of low Young's modulus and high internal viscosity). As typical of materials of this character, I may mention reclaimed rubber or, more especially, pliable cellulose nitrate plastic.

The anti-resonant structure so formed is characterized by a stiffness which is made up of that of the spring 9 together with such slight stiffness as the damping slab 11 inherently possesses; by a resistance which is substantially wholly contributed by the damping slab 11; and by masses which are of course obvious. The elements are so apportioned that the structure is tuned to a frequency slightly less than that of the disturbing resonance first abovementioned. By this anti-resonant structure, the mechanical admittance (reciprocal of impedance) characteristic for the complete system, as seen by the record R looking into the tool 5, is altered from one exhibiting a large sharply peaked value at the frequency of the resonance abovementioned to a characteristic exhibiting two peaks, but each of far lower—and in typical cases quite negligible—amplitudes and of broader frequency width. The presence of sharp peaks in this admittance characteristic is found to be a measure of the undue vibratory tendencies of each component of the complete system; accordingly it will be understood that these tendencies may be vastly reduced by the practice of the invention. And although the anti-resonant structure is attached to the main portion of the recorder, with respect to which the unit 4 and tool 5 are vibratable by the input oscillations, the undue vibration of the latter elements with respect to the main recorder portion is effectively suppressed.

It will be understood that if the damping means be chosen to have too high a resistance, the reduction of the undue vibrations will be inefficient (even the tuning of the structure being defeated in the extreme case of infinite resistance by reason of the effective rigidifying of the structure, rendering it effectively a pure mass). On the other hand, too low a resistance of the damping means will result in replacing an initial highly objectionable resonance with two different-frequency resonances each almost as objectionable as the first. There is between these two extremes, however, quite a wide range of useful resistances, values within which are readily chosen by test in any particular case—of, if desired, by calculations which apply, to the instant structure, the purely general data presented in the Den Hartog publication abovementioned.

As a wholly illustrative and non-limitative example of dimensioning of components of a sys-

tem such as that illustrated, wherein the recorder itself had an effective mass as seen at the tool 5 of about 4 grams and produced a resonance with the dynamic compliance of the record R at a frequency of about 200 cycles per second, I may mention the use of a damping slab 11 of the pliable cellulose nitrate plastic identified commercially as Du Pont "Viscoloid" type X7775, of $\frac{1}{8}$ " thickness, $\frac{5}{8}$ " length and $\frac{1}{2}$ " width; and of a spring 9, formed immediately thereabout as illustrated, from .003" thick Swedish spring steel.

I may call attention to the fact that the effectiveness of a structure of the type disclosed may, generally speaking, be increased by increasing its width (i. e., that of the slab 11 and spring 9)—and that, assuming the structure initially is properly tuned, this width increase need not ordinarily be accompanied by the change of any other dimension. This results from the fact that, although the mass of the structure is obviously changed, the stiffness is simultaneously changed in quite counteracting degree. In the illustrated recorder I have employed a structure width slightly greater than the recorder width—avoiding a still higher structure width only for secondary reasons of objectionable bulk.

Further to aid the effectiveness of the structure it is desirable when possible that it extend to a substantially greater distance from the axis of pivots 2 than the distance from that axis of the tool 5; this results in a step-up of the movements of the recorder as those movements tend to appear in the anti-resonant structure. It is also desirable that the beam or cantilever be disposed at least very approximately along a radial line or plane from the pivoting axis. Both of these desiderata, attaching when the member to which the structure is secured is a pivoted one, are embodied in the system of Figures 1 and 2.

It is to be understood that the direct securing of the anti-resonant structure to the recorder (e. g., to the casing 3) is simply one means of coupling it thereto, and that other coupling means may be employed if desired. Thus in Figure 1a I have illustrated an alternative arrangement, wherein the anti-resonant structure is coupled to the casing 3 through a link system. In this figure the standard 4 is shown with an upwardly extending arm 1'. At the extremity of this arm are provided pivots 2', and to these is pivoted a short double-armed lever 6''. To the left-hand extremity of one of the arms of lever 6'' is pivotally connected (at P₁) the top extremity of a link 15, of which the bottom extremity is pivotally connected (at P₂) to the bracket 14 (i. e., to one of its arms 13); thus lever 6'' becomes a secondary element in the system, linked to the primary movable element (e. g., casing 3) for simultaneous movement therewith. To the right-hand extremity of the arms of lever 6'' is secured a clamp 6', which may be quite similar (excepting for its position) to the clamp 6 of Figure 1. In this clamp are provided the screws 8 and stop bushings 7 described in connection with Figure 1; and in the clamp is terminally held the anti-resonant structure 9—10—11 as also above described.

In this arrangement not only does the link provide a coupling means between casing 3 and the anti-resonant structure but also, if the distance of P₂ from 2 is made large relative to the distance of P₁ from 2' as shown, there is provided a very material step-up of the recorder movement as this appears in the damped

anti-resonant structure. There is also to be noted the fact that the anti-resonant structure in this case provides some counterbalancing of the recorder, in distinction to its provision of some additional bias in the arrangement of Figure 1. It will of course be understood that the several features of link coupling, motion step-up, and counterbalancing arrangement are available separately or in other combinations than that of all three simultaneously.

It will be appreciated that, since the damping slab 11 does have some apparent stiffness as well as mass and resistance, it may in cases be possible to employ for the anti-resonant structure a beam formed of it alone. But latitude of adjustment of resistance relative to reactance values, for optimum effectiveness, is then destroyed. Furthermore many otherwise suitable materials show tendencies to some "flow" and to rather indefinite restoration characteristics; these tendencies are rendered harmless by the association, with the unsecured extremity of the damping slab, of the means for retaining the slab against deformation which the spring and spring clamp 9-10, actually provide.

The damped anti-resonant structures which I may utilize are not limited to single cantilever form; they may for example comprise a double cantilever (i. e., centrally clamped beam) structure such as shown in Figures 3 and 4. Herein is seen the clamp 16, for example welded to the top of casing 3, and having the top and bottom clamping surfaces 16' and 16'', respectively. Screws 18 are provided for drawing these surfaces together, and surrounding each screw between the clamping surfaces may be a stop bushing 17. The central portion of thin spring 19 is clamped between the top of the stop bushings and the top clamping surface 16'; each end of the spring is doubly folded over to form a respective spring clamp 20. In the two spring clamps 20 are held the ends of a damping slab 21, the center of the slab being clamped between spring 19 and the bottom clamping surface 16''. In respect of tuning and effectiveness, the double cantilever structure is in general similar to a single cantilever of length equal to the dimension from the center clamp to the extremity, and of width equal to twice the width, of the double cantilever.

In Figures 3 and 4 I have illustrated, in association with the damping slab—more particularly, in immediate association with spring 19 (e. g., with the clamp portions 20 thereof)—localized masses 22, for example in the form of bars welded or otherwise secured to the spring at the points mentioned. By employing these additional masses the latitude of adjustment of reactance and resistance values, for optimum effectiveness at desired frequencies, is still further increased. It will of course be understood that such localized masses may be added in a variety of forms and manners, that the illustration thereof is not to be taken as limitative, and that their use is not limited to the particular double cantilever arrangement of these figures but is available in any of the embodiments of my invention.

The damped anti-resonant structure may also be a "clamped-clamped" beam—i. e., secured at both extremities; in this event the retention against deformation of the slab of damping material is inherently fairly well provided, and spring means may be employed or not more purely in accordance with the tuning require-

ments. I have illustrated this form of structure in Figure 5 (without spring) and in Figure 6 (with spring), applied to a translating device not peculiar to vibration recordation—i. e., applied to a loudspeaker. In these figures the magnetic structure of a dynamic loudspeaker appears as 30, energized as by field-coil 31 and having the annular gap 32. Extending from in front into the gap is the annular voice-coil supporting member 33, carrying the voice-coil 34, and supported for movement longitudinally of the gap by resilient means schematically indicated as springs 35. Secured to the front of the annular member 33 is the cone or other diaphragm 36; and it will be understood that by the supply of electric oscillations to the voice-coil 34, the moving system comprising that coil with the member 33 and the diaphragm will be caused to vibrate in correspondence with those oscillations. In this vibration it is well understood that one or more peaks of undue amplitude may occur—for example, at the frequency of resonance of the mass of the moving system with the compliance of the resilient supporting means 35. For the reduction or suppression of this peak I may place, on opposite internal surfaces of the annular member 33, spring clamps 37, and in these clamps hold the opposite extremities of a damping slab 38—preferably of such material as above-mentioned. Figure 6 indicates a permissible special configuration of the beam, and the permissible employment therewith of spring means 39 held by the clamps 37 in contact with one or both sides of the slab 38, as for facilitation of the proper tuning of the structure to or slightly below the frequency of the peak to be suppressed. Still further, Figure 6 illustrates the permissible association with the anti-resonant structure of a localized mass 42—for example, a small block of steel welded to the central portion of spring 39.

It will be understood that while my invention has certain special utility with vibration recorders, it may be in cases employed to advantage with phonographic and other vibration reproducers, as well as with other forms of translating devices. And while I have shown certain anti-resonant structures in a particular association with an oscillation recorder, and have shown another anti-resonant structure in association with another form of translating device, I do not intend any unnecessary limitations by virtue of these particular groupings of elements. Rather I undertake to express the proper scope of my invention in the appended claims, subject only to such limitations as the state of the art may impose.

I claim:

1. In a system including a tool for recording oscillations upon a moving record: a recorder comprising a tool-carrying portion vibratable in accordance with plural-frequency input oscillations; a portion supporting said tool-carrying portion and mounted for movement toward and away from the record; and a tuned and damped vibration absorber directly coupled to said supporting portion and effective as to vibrations toward and away from the record.

2. In a phonographic system including a stylus for co-operating with a moving record: a translating device comprising a vibratable stylus-carrying portion; a portion supporting said stylus-carrying portion and mounted for movement toward and away from the record; and a tuned and damped vibration absorber directly coupled to

said supporting portion and effective as to vibrations toward and away from the record.

3. In a phonographic system including a stylus for co-operating with a moving record: a translating device comprising a vibratable stylus-carrying portion; a portion supporting said stylus-carrying portion and mounted for movement toward and away from the record; and damped tuned anti-resonant means, directly coupled to said supporting portion and effective as to vibrations toward and away from the record, for damping excessive vibrations of said stylus.

4. In a phonographic system including a stylus for co-operating with a moving record: a translating device comprising a vibratable stylus-carrying portion; a portion supporting said stylus-carrying portion and mounted for movement relative to the record; and a damped resilient beam structure, tuned to a frequency approximating the frequency of resonance of the effective mass of the translating device with compliance characterizing the system, and directly coupled to said supporting portion.

5. In a phonographic system including a stylus for co-operating with a moving record: a translating device comprising a vibratable stylus-carrying portion; a portion supporting said stylus-carrying portion and mounted for movement relative to the record; and a damped vibration absorber directly coupled to said supporting portion and tuned for effective action in the frequency region of resonance of the effective mass of the translating device with compliance characterizing the system.

6. In a system including a tool for recording oscillations upon a moving record: a recorder comprising a tool-carrying portion vibratable in accordance with plural-frequency input oscillations; a portion supporting said tool-carrying portion and mounted for movement toward and away from the record; and a damped anti-resonant structure coupled to said supporting portion and tuned to a frequency approximating the frequency of resonance of the effective mass of the recorder with the sum of the dynamic compliance of the record and the compliance of said tool-carrying portion.

7. In a system including a tool for recording oscillations upon a moving record: a recorder comprising a tool-carrying portion vibratable in accordance with plural-frequency input oscillations; a portion supporting said tool-carrying portion and mounted for movement toward and away from the record; and tuned anti-resonant means, directly coupled to said supporting portion, for suppressing excessive vibrations of said tool in the frequency region of resonance of the

effective mass of the recorder with the sum of the dynamic compliance of the record and the compliance of said tool-carrying portion.

8. In a phonographic system including a stylus for co-operating with a moving record: a translating device comprising a vibratable stylus-carrying portion; a portion supporting said stylus-carrying portion and mounted for movement toward and away from the record; and tuned anti-resonant means, coupled to said supporting portion in counterweighting arrangement thereto and effective as to vibrations toward and away from the record, for suppressing excessive vibrations of said stylus in the frequency region of resonance of the effective mass of the recorder with compliance characterizing the system.

9. In an oscillation-translating system: a movable element forming a portion of said system; and damping means effective on said element comprising a spring secured to and extending from said element, and a slab of damping material of high internal resistance retained in contact with said spring.

10. In an oscillation-translating system: a movable element forming a portion of said system; and damping means effective on said element comprising a spring secured to and extending from said element, and a slab of damping material of high internal resistance also extending from said element, the outer end of said spring being folded over to engage the end of said slab.

11. In an oscillation-translating system: a movable element forming a portion of said system; and damping means effective on said element comprising a slab of damping material of high internal resistance secured to and extending from said element, and means associated with the outer end of said slab for retaining said slab against permanent deformation.

12. In an oscillation-translating system: a movable element forming a portion of said system; and damping means effective on said element comprising a spring secured to and extending from said element, a slab of damping material of high internal resistance retained in contact with said spring, and a mass associated with a vibratable portion of said spring.

13. In an oscillation-translating system: a movable element forming a portion of said system; and damping means effective on said element comprising a slab of damping material of high internal resistance secured to and extending from said element, and a localized mass associated with said slab.
